(57) **CLAIM**

The ornamental design for a serving platter system, as shown and described.

DESCRIPTION

FIG. 1 is a top perspective view of the serving platter system showing my new design.

FIG. 2 is a top view of the serving platter system of FIG. 1. FIG. 3 is a bottom view of the serving platter system of FIG. 1.

FIG. 4 is a front view of the serving platter system of FIG. 1 with the cutting board portion separated from the platter portion.

FIG. 5 is a section view showing a bottom view of the cutting board portion of the serving platter system of FIG. 1. FIG. 6 is a section view showing a top view of the platter portion of the serving platter system of FIG. 1.

FIG. 7 is a rear view of the serving platter system of FIG. 1 with the cutting board portion separated from the platter portion.

FIG. 8 is a left-side view of the serving platter system of FIG. 1 with the cutting board portion separated from the platter portion.

FIG. 9 is a right-side view of the serving platter system of FIG. 1 with the cutting board portion separated from the platter portion.

FIG. 10 is a bottom perspective view of the serving platter system of FIG. 1 with the cutting board portion separated from the platter portion; and,

FIG. 11 is a top perspective view of the serving platter system of FIG. 1.

The broken lines in the figures show portions of the serving platter system and form no part of the claimed design.

1 Claim, 11 Drawing Sheets
